PINBALL AMUSEMENT GAME

Herbert G. Breitenstein, Chicago, Ill., assignor to
Raymond T. Moloney, Chicago, Ill.

Application January 16, 1935, Serial No. 2,078

7 Claims. (Cl. 273—121)

The invention relates to an improvement for use in connection with amusement games of skill of the pin ball type.

These games embody a play board, or table, inclined slightly from the horizontal to provide a surface over which free balls are rolled to drop into, or through, holes formed in the board. A projector serves to roll the balls, one at a time, through a passage to be guided to a yieldable, or spring bumper from which the balls rebound to roll by gravitation down the sloped board to be received by the holes.

In the present invention this rebound bumper is placed at the entrance to a ball passageway and normally is disposed to obstruct the entrance to said passageway. However, in the event a skilfully projected ball is dropped through a certain control hole, a mechanism, which is preferably electrically operated and ball controlled, is operative to swing, or move, the rebound bumper from its normal position to expose or open the entrance to the passageway associated therewith to enable a subsequently projected ball to pass the bumper and enter the said passageway for movement to an area on the board having score holes of a high value.

The main object of the invention, therefore, is to provide a yieldable or resilient rebound bumper which is movable from a position closing the entrance to a ball passageway to a position opening said entrance for the reception of a subsequently played ball.

Another object is to provide a ball controlled electrically actuated mechanism for moving said rebound bumper.

Still another object is to associate with the bumper, means actuated directly by a ball entering the opened passageway to move the rebound bumper back to entrance closing position.

These and other objects, may be attained in practice by the illustrative example of the invention shown in the accompanying sheet of drawings, wherein:

Figure 1 is a general plan view of a pin ball game embodying the improved rebound bumper and control mechanism therefor;

Figure 2 is a longitudinal, central sectional view through the game taken along the line 2—2 of Figure 1, looking in the direction of the arrows;

Figure 3 is an enlarged, detail plan view, with a portion of the game board broken away, to illustrate the spring bumper in its normal passageway closing position;

Figure 4 is a similar view showing the bump-

er moved to passageway opening position; and, Figure 5 is a vertical, longitudinal, detail sectional view through the bumper and its operating mechanism taken along the line 5—5 of Figure 3, looking in the direction of the arrows.

The game comprises the usual rectangular box 10 having a front wall 11, in which box is supported a play board 12 sloped slightly from the horizontal with its lower end adjacent the front wall 11. The open top of the box is closed by a glass panel 13. Along the right hand side of the board 12 is a longitudinal partition 14 forming a ball projection passageway 15 at the lower end of which is a ball projector 16 mounted in the front wall 11. The upper end of the board is provided with a rounded edge 17 forming means to guide projected balls to a spring bumper element 18 from which balls may rebound to the top end of the board for gravitation downhill.

Balls gravitating in this fashion may be trapped by any one of a number of holes 19 formed through the board 12. Balls lodged in these holes are supported in the usual way by a shiftably mounted under panel 20 having holes 21 formed therethrough in offset relation with respect to the upper holes 19. Balls missing the holes 19 gravitate to a slot 22 at the lower edge of the board where they remain for the time being supported by the lower edge of the panel 20 in an obvious and well known manner.

Below the panel 20 the cabinet carries a sloped ball routing panel 23 which is stationary and functions, as will presently appear, to direct released balls to a transverse trough 24 which is inclined toward the right hand side of the box to be delivered into a ball lift groove 25 formed in the adjacent wall of the box from whence, in a well known manner they may be lifted one at a time, by a lifter 26 from the trough 24 to a position in the lower end of the passageway 15 to be projected by the projector 16, said lifter being manually actuated in the usual way, by a plunger 27 carried in the front wall 11 of the box 10.

The front wall of the box also carries a coin release slide 28 the inner end of which is adapted to abut to a bracket 29 formed adjacent the lower edge of the panel 20 whereby to push the said panel 20 rearwardly to register the holes 21 therein with the holes 19 in the play board 12 to cause the balls to be released and to drop onto the routing panel 23 for delivery to the trough 24. Balls in the slot 22 in the same manner are released to fall on an inclined member 30 for delivery to the trough 24.

At the left hand edge of the board 12 is a longitudinal partition 31 forming a passageway 32 that may lead to a curved deflector 33, or other means for directing a ball for movement over the board to be trapped by any suitably placed hole or other ball trap of a high scoring value. Balls lodging in the pocket formed by this deflector 33 are received by a slot 34 from whence they may be released in the manner described by shifting 10 the ball release panel 20.

The bumper 18 heretofore described comprises in the present embodiment of the invention, a resilient hairpin member having its legs secured to collars 35 movable with a vertical shaft 36 journalled in a bearing 37 carried in the board 12. Also mounted on the shaft 36 to turn therewith is an angularly related trip leg 38 adapted to seat in a notch 39 formed in the adjacent face of the partition, it being noted that the shaft 36 is positioned just to the rear of the rear end of said partition 31.

Said shaft 36 projects downwardly a distance below the board 12 where it carries fixed thereto a collar 40 including a crank arm 41 having its free end slotted as at 42 to slidably receive a pin 43 for pivotally connecting said crank 41 with the armature 44 of a solenoid 45 carried by a bracket 46 on the under side of the board 12.

Near the upper end of the board 12 is formed 30 a control hole 47 below which on the panel 23 is mounted a channel member 48 carrying a flat spring switch member 49 adapted to receive a ball falling through the hole 47 to contact the same with another flat spring conductor member 50 to 35 momentarily establish or close an electric circuit including a wire 51 connected between the contact member 50 and a battery 52 appropriately carried on the floor 53 of the box 10. Another wire 54 connects between the switch member 49 and the solenoid 45 while another wire 55 connects between the battery 52 and solenoid 45 as shown.

In starting the game play the coin slide 28 is actuated to slide or shift the panel 20 as described to release all balls for return to the trough 24 45 from whence they are lifted to position to be projected by the projector 16. These projected balls roll to the upper end of the board and along the track 17, if sufficient force is used, to engage the spring bumper 18 which is normally in a position 50 obstructing the entrance to the passageway 32. Consequently, the ball hits said bumper and resiliently is rebounded therefrom to the high end of the board for gravitation theredown possibly to be caught by the score holes 19 or the slot 22 in 55 a manner well understood in the art. Should a skilfully directed ball be dropped through the hole 47, said ball will be received in the channel member 48 to close the spring contact switch therein to establish an electric circuit, as described, for energizing the solenoid 45. Thereupon the armature 44 pulls forwardly on the crank 41 to rock the shaft 36 to swing the bumper spring 18 from the passage closing position of Figure 4 to passage opening position as shown in Figure 4. Thereupon a subsequently played ball 60 directed to the bumper engages the trip leg 38 which then swings back against the wall 31, and in its notch 39, to permit the ball to move down the passage 32. As the trip arm so moves, the bumper spring 18 is swung back to passage closing 65 position in an obvious manner.

The ball rolling down said passage 32 is deflected by the deflector 33 back onto the board in the direction of any suitable holes or the like 70 having high score values. The control ball that

fell through the hole 47 by this time has rolled out of the channel 48 so that the spring contacts automatically separate to break the circuit to the solenoid, the control ball now rolling down the panel 23 for return to the trough 24.

When a ball rolls past the trip leg 38 into the passage 32 the movement of the bumper 18 back to passage closing position is utilized through turning of the shaft 36 to pull the armature 44 through the crank 41, out of the solenoid as 10 shown in Figure 3 to reset the same for a subsequent operation as will be readily understood.

It is the intention to cover all changes and modifications of the ball controlled, automatically moved bumper rebound spring, and its association with pin ball, or the like, game structures as herein particularly illustrated, for obviously the bumper may assume various forms and be employed in varying relationships and organizations without departing from the invention.

What is claimed is:

1. In a game of the class described having a play board inclined from the horizontal and provided with ball receiving holes, a projector for rolling balls onto the board, a movably mounted resilient member operatively associated with the board to be hit by projected balls so that they rebound therefrom for gravitation toward said holes, and means controlled by the projection of a ball to move said resilient member out of the path of movement of a subsequently projected ball to prevent such ball from rebounding therefrom.

2. In a game of the class described having a play board inclined from the horizontal and provided with ball receiving holes, a projector for rolling balls onto the board, a movably mounted resilient member operatively associated with the board to be hit by projected balls so that they rebound therefrom for gravitation toward said holes, and means controlled by the dropping of a ball through a certain other hole formed through the board to move said resilient member out of the path of movement of a subsequently projected ball to prevent such ball from rebounding therefrom.

3. In a game of the class described having a play board inclined from the horizontal and provided with ball receiving holes, a projector for rolling balls onto the board, a movably mounted resilient member operatively associated with the board to be hit by projected balls so that they rebound therefrom for gravitation toward said holes, and means controlled by the dropping of a ball through a certain other hole formed through the board comprising an electrical device to move said resilient member out of the path of movement of a subsequently projected ball to prevent such ball from rebounding therefrom.

4. In a game of the class described having a play board inclined from the horizontal and provided with ball receiving holes, a projector for rolling balls onto the board, a movably mounted resilient bumper operatively associated with the board and normally positioned to obstruct the entrance to a passageway formed on the board, said bumper in such position lying in the path of movement of the projected balls to cause them to strike and rebound from the bumper for gravitation down the board toward the holes therein, and means operable by the dropping of a ball through a certain hole formed through the board to move said bumper from its passageway obstructing position to permit a subsequently projected ball to enter said passageway.

5. In a game of the class described having a

play board inclined from the horizontal and provided with ball receiving holes, a projector for rolling balls onto the board, a movably mounted resilient bumper operatively associated with the board and normally positioned to obstruct the entrance to a passageway formed on the board, said bumper in such position lying in the path of movement of the projected balls to cause them to strike and rebound from the bumper for gravitation down the board toward the holes therein, and ball controlled electrically operable means for moving said bumper from its passageway obstructing position to permit a subsequently projected ball to enter said passageway.

5 6. In a game of the class described having a play board inclined from the horizontal and provided with ball receiving holes, a projector for rolling balls onto the board, a movably mounted resilient bumper operatively associated with the board and normally positioned to obstruct the entrance to a passageway formed on the board, said bumper in such position lying in the path of movement of the projected balls to cause them to strike and rebound from the bumper for gravitation down the board toward the holes therein, ball controlled electrical means operable to move said bumper from its passageway obstructing position to permit a subsequently projected ball to enter said passageway, and means actuated by a ball entering said passageway to move the bumper back to its passageway obstructing position.

10 20 25

a certain hole formed through the board to move said bumper from its passageway obstructing position to permit a subsequently projected ball to enter said passageway, and a trip associated with the bumper and actuated by the ball entering said passageway to move the bumper back to its initial passageway obstructing position.

5

7. In a game of the class described having a play board inclined from the horizontal and provided with ball receiving holes, a projector for rolling balls onto the board, a movably mounted resilient bumper operatively associated with the board and normally positioned to obstruct the entrance to a passageway formed on the board, said bumper in such position lying in the path of movement of the projected balls to cause them to strike and rebound from the bumper for gravitation down the board toward the holes therein, ball controlled electrical means operable to move said bumper from its passageway obstructing position to permit a subsequently projected ball to enter said passageway, and means actuated by a ball entering said passageway to move the bumper back to its passageway obstructing position.
